[57] CLAIM

The ornamental design for a guide bar for chain saw, as shown and described.

DESCRIPTION

FIG. 1 is a left side elevational view of a guide bar for chain saw showing my new design, the right side being a mirror image thereof;
FIG. 2 is a top plan view of FIG. 1, the bottom being a mirror image thereof;
FIG. 3 is a rear elevational view of FIG. 1;
FIG. 4 is a front elevational view of FIG. 1; and
FIG. 5 is a perspective view of FIG. 1;
FIG. 6 is a left side elevational view of a second embodiment of a guide bar for chain saw showing my new design of FIGS. 1-5, the right side being a mirror image thereof;
FIG. 7 is a top plan view of FIG. 6, the bottom being a mirror image thereof;
FIG. 8 is a rear elevational view of FIG. 6;
FIG. 9 is a front elevational view of FIG. 6; and
FIG. 10 is a perspective view of FIG. 6;
FIG. 11 is a left side elevational view of a third embodiment of a guide bar for chain saw showing my new design of FIGS. 6-10, the right side being a mirror image thereof;
FIG. 12 is a top plan view of FIG. 11, the bottom being a mirror image thereof;
FIG. 13 is a rear elevational view of FIG. 11;
FIG. 14 is a front elevational view of FIG. 11; and
FIG. 15 is a perspective view of FIG. 11;
FIG. 16 is a left side elevational view of a fourth embodiment of a guide bar for chain saw showing my new design of FIGS. 11-15, the right being a mirror image thereof;
FIG. 17 is a top plan view of FIG. 16, the bottom being a mirror image thereof;
FIG. 18 is a rear elevational view of FIG. 16;
FIG. 19 is a front elevational view of FIG. 16; and
FIG. 20 is a perspective view of FIG. 16;
FIG. 21 is a left side elevational view of a fifth embodiment of a guide bar for chain saw showing my new design of FIGS. 16-20, the right being a mirror image thereof;
FIG. 22 is a top plan view of FIG. 21, the bottom being a mirror image thereof;
FIG. 23 is a rear elevational view of FIG. 21;
FIG. 24 is a front elevational view of FIG. 21; and
FIG. 25 is a perspective view of FIG. 21;

FIG. 26 is a left side elevational view of a sixth embodiment of a guide bar for chain saw showing my new design of FIGS. 21-25, the right being a mirror image thereof;

FIG. 27 is a top plan view of FIG. 26, the bottom being a mirror image thereof;
FIG. 28 is a rear elevational view of FIG. 26;
FIG. 29 is a front elevational view of FIG. 26; and
FIG. 30 is a perspective view of FIG. 26.
